UNITED STATES PATENT OFFICE.

HUBERT BAILEY, OF NEW YORK, N. Y.

POLISHING TOOL.

Application filed May 20, 1922. Serial No. 562,345.

To all whom it may concern:

Be it known that I, HUBERT BAILEY, a citizen of the United States, and a resident of the city of New York, borough of the Bronx, 5 in the county of Bronx and State of New York, have invented new and useful Improvements in Polishing Tools, of which the following is a full, clear, and exact description.

10 This invention relates to polishing tools primarily designed for use as toothbrushes.

In the construction of polishing tools it is a great advantage if the tool may be easily disassembled for the replacement of parts.

15 If the polishing tool is to be used as a toothbrush it is very essential that the device be small and compact so that it may be projected into the mouth to reach any of the teeth. Further, when the device is used as 20 a toothbrush it is important that all the parts that are subject to any considerable wear should be capable of replacement so that after the initial outlay has been made for the polishing tool it may be kept in condition at a very small cost.

25 The general object of this invention is the provision of a simple, compact and efficient polishing tool that may be easily disassembled for cleaning and the replacement of 30 parts.

A further object of this invention is the provision of a polishing tool that may be associated with any water supply system and driven thereby.

35 These objects are accomplished by providing a two-piece casing, the head section of the casing having mounted therein a hollow shaft carrying a brush and a bevel gear, both removably mounted thereon, said hollow shaft being retained in position when the head section is attached to the tubular section of the casing by the driving means which engages with the gear mounted on the hollow shaft, and associating with the driving means a prime mover.

40 These and other objects of the invention will be more clearly understood from the following detailed description and accompanying drawings.

45 Figure 1 is a vertical longitudinal section through the casing showing the construction of the polishing tool;

Figure 2 is a section along the line 2-2, Figure 1;

50 Figure 3 is an exploded view of the hollow shaft and thrust bearing, and the means

for connecting the brush to the hollow shaft;

Figure 4 is a section through the bearing which serves to connect the two sections of the casing together;

60

Figure 5 is a side elevation of the bevel gear that is connected to the driving shaft;

Figure 6 is a side elevation of the driving shaft;

Figure 7 is a section through the bearing 65 removably mounted in the tubular section of the casing.

Referring to the above-mentioned drawings, a casing assemblage 10 is made up of a tubular section 11 and a head section 12. 70 The tubular section 11 has an enlarged end 37 provided with an external thread for mounting it in a turbine casing 13. This enlarged portion 37 is circular and concentric with the tubular section 11. Thus when 75 it is mounted in the turbine casing 13 the tubular section 11 is mounted in alignment with the axis of the turbine wheel 14. Two bearings 15 and 16, which are provided with external threads are removably mounted in 80 the ends of the tubular section 11 which is provided with internal threads. The bearing 16 extends beyond the end of the tubular section 11, and the head section 12 of the casing is mounted on this bearing.

85

Rotatably mounted in the bearing 16 is a shaft 17 to which a bevel gear 18 is attached. The end 19 of this shaft is threaded. Mounted in alignment with the shaft 17 is a shaft 20. This shaft 20 has two threaded openings 23 and 39 extending inward from opposite ends along its axis. The threaded end 19 of the shaft 17 makes threaded engagement in either of the two openings 23 or 39 in the shaft 20, serving to support one end 95 of the shaft while the other end of the shaft is supported by the bearing 15. A screw 24 which makes threaded engagement in either of the openings 23 or 39 of the shaft 20 is provided for attaching the plate 22 to the 100 shaft. From the above it will be seen that the shaft 20 is reversible so that when one end is worn by use it may be reversed.

The head section 12 of the casing has a chamber 25 provided therein, the horizontal 105 cross section of which is circular. Located in this casing in vertical position is a bearing post 26 which carries a removable thrust bearing 27. A hollow shaft 28, having an internal thread 29 in its upper end and an 110 external thread 38 on its lower end, has a brush 30 attached to the upper end of the

2
hollow shaft by means of a threaded nipple 31. The upper end of this threaded nipple is of greater diameter than the lower end so that when the lower end makes threaded engagement with the internal thread in the hollow shaft 28 the upper end seats on a washer 33 located between the hollow shaft and nipple. A bearing face 32 adapted to seat on the thrust bearing 27 is formed in the lower end of the nipple 31. A bevel gear 34 having an internal thread 35 is removably mounted on the lower end of the hollow shaft, the internal thread 35 of the gear engaging with the external thread 38 cut on the shaft 28. Thus the bevel gear 34 and the brush 30 are mounted on opposite ends of the hollow shaft and spaced from one another. This hollow shaft is then positioned over the thrust bearing 27 and the bearing post 26 extending at right angles to the shaft 20. The gear 18 projects into the space between the brush 30 and the gear 34, meshing with the latter and serving to retain the hollow shaft in position on the bearing. A collar 36 is mounted in the head section of the casing, surrounding the gear 34 and forming a second bearing for the gear wheel 34. This collar is removably mounted so that it may be reversed when the lower end has become worn.

The operation of this device is very simple. The turbine wheel is connected to any water supply which sets it in operation. This revolves the shaft 20, and the motion of the shaft 20 is conveyed to the shaft 17, gear 18, gear 34 to the hollow shaft 28 which rotates the brush 30.

In disassembling this polishing tool, the casing section 12 is removed from the bearing 16. This releases the gear 34 and the hollow shaft drops off the bearing 27. Then any of the parts mounted on the hollow shaft may be removed and replaced. The bearings 15 and 16 may also be removed and replaced with very little difficulty. The shaft 20 may be reversed so as to give a new bearing end in the bearing 15.

I would state in conclusion that while the illustrated example constitutes a practical embodiment of my invention, I do not limit myself strictly to the exact details herein illustrated, since manifestly the same can be considerably varied without departing from the spirit of the invention as defined in the appended claims.

Claims:

1. A polishing tool including a casing and a driving shaft, said casing being provided with a hollow cylindrical head, a thrust bearing mounted in the bottom of said cylindrical head, a bevel gear rotatably mounted on the thrust bearing, a second bevel gear

carried by the driving shaft positioned above the first-mentioned bevel gear, meshing with it and serving to retain it in position on said thrust bearing, a brush rotatably mounted in the casing and means for driving the brush from the bevel gear mounted on the thrust bearing.

2. A polishing tool including a casing having a hollow cylindrical head, a bearing located in the bottom of said hollow cylindrical head, a bevel gear loosely mounted on said bearing, a drive shaft rotatably mounted in the casing, a second bevel gear mounted on the end of said shaft located above the first-mentioned bevel gear and meshing with it serving to retain it in position on the bearing and a brush rotatably mounted in said hollow cylindrical head and connected to the bevel gear mounted in the bearing located in the bottom of the hollow cylindrical head.

3. In a polishing tool of the class described, a casing, a polishing brush and a bevel gear mounted on a hollow shaft and spaced from one another, said hollow shaft being mounted on a thrust bearing positioned in the casing, a driving shaft rotatably mounted in movable bearings positioned in the casing and extending at right angles to the hollow shaft, and a bevel gear, mounted on the end of the shaft and projecting into the space between the bevel gear and polishing brush, meshing with the bevel gear mounted on the hollow shaft, serving to drive the latter and to retain the hollow shaft in position in the casing.

4. A polishing tool, comprising a casing, a thrust bearing fixed in the casing, a hollow shaft rotatably mounted on the thrust bearing, a brush and bevel gear carried by the hollow shaft and spaced apart, the gear being located in the bottom of the casing, a second bevel gear extending between the brush and the bevel gear mounted on the hollow shaft, said second bevel gear meshing with the bevel gear mounted on the hollow shaft, and a drive shaft mounted in the casing carrying said second bevel gear.

5. In a polishing tool of the class described, including a casing and a driving shaft, a hollow shaft, a polishing brush, a nipple having a bearing face provided in one end associated with the brush and hollow shaft for attaching the former to the latter, a bevel gear mounted on the lower end of said hollow shaft and spaced from the polishing brush, and a bevel gear mounted on the driving shaft projecting into the space between the bevel gear carried by the hollow shaft and the polishing brush meshing with the former.

HUBERT BAILEY.
